CLAIM

The ornamental design for a cup holder pillow, as shown and described.

DESCRIPTION

FIG. 1 is a top perspective view of a cup holder pillow showing my new design;

FIG. 2 is a front elevational view thereof, the rear elevational view being a mirror image;

FIG. 3 is a left side elevational view thereof, the right side elevational view being a mirror image;

FIG. 4 is a top plan view thereof;

FIG. 5 is a bottom plan view thereof; and,

FIG. 6 is a right cross-sectional view thereof taken along the line 6-6 of FIG. 2.

1 Claim, 6 Drawing Sheets
